V. WILLOUGHBY,

COUPLING FOR MINE CARS,

APPLICATION FILED DEC. 30, 1915.

1,224,824.

Patented May 1, 1917.

Victor Willoughby

J. H. Gibbs

UNITED STATES PATENT OFFICE.

VICTOR WILLOUGHBY, OF JEFFERSONVILLE, INDIANA, ASSIGNOR TO AMERICAN CAR AND FOUNDRY COMPANY, OF ST. LOUIS, MISSOURI, A CORPORATION OF NEW JERSEY.

COUPLING FOR MINE-CARS.

1,224,824.

Specification of Letters Patent.

Patented May 1, 1917.

Application filed December 30, 1915. Serial No. 69,400.

To all whom it may concern:

Be it known that I, VICTOR WILLOUGHBY, residing at Jeffersonville, Clark county, Indiana, and being a citizen of the United States, have invented certain new and useful Improvements in Couplings for Mine-Cars, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings:

20 Figure 1 is a plan view of the improved coupler shown as joining fragmentary portions of the opposing ends of juxtaposed cars.

25 Fig. 2 is a vertical longitudinal section taken on the line 2—2 of Fig. 1, the direction of vision being indicated by the arrows, and

30 Fig. 3 is a transverse section through the coupler, being taken on the line 3—3 of Fig. 2, and viewed as the arrows indicate.

The improved coupler herein disclosed is adapted to couple cars automatically, but requires manual operation to permit the uncoupling of such cars. Consequently, no other operation than the bumping of cars is required to couple those intended to be included in a train. As the cars, so coupled, cannot be detached, except by manipulation of the coupler, there is no danger of a train 35 breaking into train segments on a heavy 40 grade, or for any other reason.

Protective means are also provided for preventing the coupler from being subjected to the buffing shock consequent to the cars 45 being bumped together during the automatic coupling process.

Provision is made to prevent the failure of the automatic coupling of cars whereby the reliability of the coupler is assured. 50 Also the coupler is so designed that the cars it connects, may round sharp curves without difficulty. The other advantageous features of the invention will appear hereinafter.

In the drawing, A represents a mine car and B indicates a similar portion of the opposing end of another mine car. The end wall of car A is represented by *a* and car B is provided with a similar end wall *b* opposite the end wall of car A. A draft member or strap 1 lies on the upper surface of the floor C of the car A, being centrally disposed transversely of the car. Said strap 1 passes through a notch in the bottom of end wall *a* and projects therebeyond a considerable distance, being provided with an aperture 2 near its outer end. Lying between said outer end of strap 1 and the outer end of a bracket brace 3 is a link bracket 4 of materially greater width than that of strap 1 and bracket brace 3. The longitudinal extent of bracket 4 is disposed transversely of the cars and said bracket is provided with upturned ends 5 which serve as standards to receive a link pin 6. The latter is provided with a head and its shank finds bearings in each of the upturned ends 5 of bracket 4. The end of link pin 6 opposite the head of the pin, projects through one of the upturned ends 5 sufficiently to receive a washer 7 and a cotter pin 8, whereby said link pin is securely retained in place. A link 9 is provided with a slot 10 through which link pin 6 passes. The bracket 4 is held in rigid relation to the end of car A by a rivet 11 of substantial proportions, which passes through the hole 2 in the outer end of strap 1, the horizontally disposed portion of bracket 4 and the outer end of bracket brace 3. Rivet 11 has a countersunk head, the upper surface of which is flush with the upper surface of strap 1 and also a rounded or other shaped head at the under side of the outer end of bracket brace 3. Said outer end of bracket brace 3 is horizontally disposed for nearly the width of bracket 4, after which it becomes vertically bent and bears against the outer surface of a lug 12 depending from the under side of strap 1. Lug 12 has a width which fills the space between bracket brace 3 and the outer end of the floor C of the car A. Below the bottom of lug 12, bracket brace 3 is inclined inwardly to the under side of the car where it becomes horizontally disposed, as shown in Fig. 2.

Suitable clamping means such as a bolt, and nut 13 binds strap 1 and the lower

horizontal portion of bracket brace 3 to the bottom of the car structure and parallel to floor C. It is, of course, to be understood that any suitable number of bolts 13 and their nuts may be used, according to the 5 width of strap 1 in any particular installation. The opposing end of car B is provided with another draft member or strap 1, which projects through and beyond the end wall *b* and toward strap 1 of car A, 10 and which is also provided with a depending lug or flange 12. Strap of car B is also provided at its outer end with a hole 2, similar to that in strap 1 of car A.

15 Latch bracket 13 is formed of re-bent strap metal and has its inner ends 13^a and 13^b spaced to receive the outwardly projecting end of strap 1 of the car B. At the outer terminal of strap 1 of car B, the lower leg 13^b of latch bracket 13 is bent semicylindrically to, in effect, provide an abutment 23. At the point of the return bending of 20 latch bracket 13, the strap metal of said bracket is substantially cylindrically formed and has a central cut out portion so that 25 suitable spaced bearings 14 are provided for a latch pin 15. The latter is of greater length than the width of latch bracket 13 and is retained in place by cotter pins 16 passing through the latch pins and between 30 the cotter pins and the outside faces of the bearings 14 are interposed washers 17.

35 Mounted on latch pin 15, is a gravity latch 18, the upper end of which has a hook formation 19 and the lower end of which is in the nature of a weighted end 22. A rivet 20 similar to rivet 11 passes through the upper leg 13^a of latch bracket 13, the hole 2 of strap 1 underlying the same, the lower leg of 13^b of latch bracket 13 and 40 a horizontally disposed leg of a stop or detent angle 21 firmly clamping these elements together. The other leg of angle 21 is vertically disposed and the inner face of the weighted portion 22 of gravity latch 18 45 is adapted to contact therewith so that said gravity latch may become arrested in its clockwise rotation about latch pin 15 at a proper point.

50 The coupler parts carried by car A are disposed between bumpers 24 and those parts of the coupler carried by car B are disposed between similar bumpers 24^b. Said bumpers 24 and 24^b project outwardly from the car 55 end walls *a* and *b*, respectively, and are adapted to receive the buffing shock when said cars come together. Coupler link 9 is, therefore, immune from such shocks, for reasons to be stated later.

60 When the cars are connected in draft relation to each other the parts of the coupler are in the positions illustrated in full lines in the drawing. At this time the weighted end of gravity latch 18 is in contact with 65 the vertical leg 21 of the stop or detent angle

and said gravity latch is incapable of having clockwise rotation about latch pin 15.

Link 9 is of U shaped formation and the closed end of the U is in engagement with the inner surface of hook portion 19 of said 70 gravity latch. Said link 9 is of circular cross section except toward the disconnected ends of its legs where the cylindrical metal is flattened to give it a rectangular cross section, a slot 10 being in the flattened portion 75 of each leg 9. At the points where the cylindrical portion of the legs of link 9 are converted into the flattened end portions, beveled surfaces 25 are present. The outer ends 10^a of slots 10 are in engagement with 80 link pin 6 when the parts of the coupler are in their full line positions and the cars have the maximum separation possible when they are coupled to each other. With this maximum separation, it is impossible for the 85 closed end of the U shaped link 9 to become disengaged from the hook end 19 of the gravity latch 18 and the cars may move in either direction and remain perfectly connected by the coupler.

90 Before the cars are connected to each other, the link 9 is normally in a horizontal position and as the cars relatively approach each other the closed end of link 9 will strike the outer arcuate surface of gravity latch 95 18, and will either ride thereover and beyond the point of the hook 19 or will cause the gravity latch 18 to revolve contra-clockwise a sufficient distance to permit the end of link 9 to pass beyond the point of the 100 hook portion 19 of said gravity latch. The cars continuing to come together the closed end of link 9 will strike the end wall *b* of the car B and drive said link toward the end wall *a* of car A to the position shown in 105 dotted and dashed lines. The end 10^b of slot 10 will then be substantially in contact with link pin 6 and said link 9 has been permitted to swivel upwardly by reason of the recesses 26 at the inner edges of the horizontal 110 portion of bracket 4. The bottoms of said recesses are inclined or beveled to permit the oscillation of link 9. In the meantime buffers 24 and 24^b have come together and sustained the buffing shock while link 9 was 115 readjusting itself to the changing positions of the cars. It is to be noted that link 9 has considerable length and is dependent upon the slots 10 to permit it to escape the effect of the buffing shocks. Link 9 is given the 120 length it possesses to permit the cars to round sharp curves which the buffer 24 and 24^b would prohibit were they too closely juxtaposed.

125 The link 9 having assumed the dotted and dashed lined position, its closed end is in propinquity to the end wall *b* of car B as seen in dotted and dashed lines in Fig. 2, and the under beveled faces 25 of link 9 are 130 in tangential contact with the cylindrical

surfaces of the bearings 14 of latch bracket 13 maintaining the link 9 in an upwardly deflected position. As soon, however, as the cars begin to separate due to the motor beginning to haul the train, beveled faces 25 slide downwardly on the upper surfaces of the bearings 14 and gravity forces link 9 to assume a horizontal position in which the closed end of link 9 engages the inner or under side of the hook portion of gravity latch 18 and the parts again assume the positions shown in full lines of the drawing, the flange 21 of the stop angle causing gravity latch 18 to be rigidly held in a non-rotative position.

If gravity latch 18 for any reason sticks after the closed end of link 9 has turned it contra-clockwise on its pin 15, at the time when the cars are coming together, the outer end of bracket brace 3 will strike the then inclining weighted portion 22 of said gravity latch to force it to its normally upright position. This, of course, will only occur after the closed end of link 9 has passed beyond the hook portion 19 of said gravity latch and always insures that said latch will be in a position to receive the engagement of the closed end of the link 9 as the cars move apart when the motor begins to haul them.

Link pin 6 is above the center line of the upturned ends 5 of bracket 4 and there would be, ordinarily, a tendency to bend strap 1 carrying said bracket 4 downwardly. This tendency, however, is resisted by the bracket brace 3 which always maintains the bracket 4 and link pin 6 in their proper positions.

It has been shown that the coupler automatically connects the cars but it is necessary to operate link 9 manually to uncouple the cars. While the cars are being drawn along the maximum separation between them is maintained as previously explained. If the speed of the train is lessened, the distance between the cars may become diminished to a greater or less extent but link 9 will remain in a horizontal position, and, as soon as the speed of the train begins to pick up, the maximum distance will again be present between the cars and the parts will automatically re-establish the conditions depicted in full lines in the drawing. When, however, the train comes to a stop, each car succeeding the first one will close up automatically toward the one in advance of it, and the closed end of link 9 will retreat from the hook portion 19 of gravity latch 18 in each of the couplers between the cars. If it be decided to disconnect any of the cars, such as cars A and B, the train man need only lift the link 9 to a height greater than that of the upper surface of the hook end of gravity latch 18, whereupon movement of link 9 in a direction toward car A will effect a disconnection between said link and the

hook portion 19 of gravity latch 18. The cars are thus easily and conveniently uncoupled.

I claim:

1. In combination in a car coupling, a pivoted and slideable link deriving support from a car end, and a pivoted gravity latch and a stop supported from another car end, said link being adapted to oscillate said latch, pass therebeyond and to be driven 75 reversely by one of said car ends and caused by gravity to occupy a latch-engaging plane, said latch automatically assuming a link-engagement position and contacting with said stop.

2. In combination in car coupling means, a pivotal and slideable link supported from a car end, a pivoted gravity latch and stop supported from another car end and opposing bumpers on both car ends adapted 85 to mutually engage to relieve said link from buffing shocks, said link being adapted to be automatically placed in neutral stress position by part of the opposing car body and also to oscillate and co-operatingly interlock with said latch, the latter automatically 90 assuming a co-operating and stop-engaging position.

3. In combination in a car coupling, a pivoted and slideable link carried from a car end and adapted to be elevated for uncoupling, an oscillatory gravity latch adapted to be actuated by and interlock with said link near another car end, a pivot and a stop therefor, a supporting bracket for the latch pivot having a flat surface in a plane enabling said link to reciprocate thereon without being raised toward an unlocking altitude, and a draft member extending from the last mentioned car end, said bracket being secured thereto.

4. In combination in a car coupling, a pivotally mounted link carried near a car end, a draft member extending from another car end, a latch bracket having spaced 110 legs and a bearing, said draft member extending between said legs, a gravity latch pivotally connected with said bearing, a stop therefor lapping said bracket legs, and means rigidly combining said draft member, 115 bracket and stop, said link being adapted to oscillate said latch and interlock therewith.

5. In combination in a car coupling, a draft member extending from a car end, a 120 latch bracket of strap-like material rebent to have spaced legs between which said draft member extends and is secured to, the bracket rebent portions being shaped to form bearings, a pivot supported by said bearings, a gravity latch mounted thereon, a latch stop and a pivotally mounted link carried near another car end adapted to oscillate said latch and interlock therewith.

6. In combination in a car coupling, a 130

draft member extending from a car end, a latch bracket, said member and bracket having interleaved portions, an oscillatory gravity latch pivotally connected with said bracket, an angle-shaped latch stop having a leg extending parallel with the interleaved draft member and bracket portions, means rigidly connecting said draft member, bracket and stop leg and a pivotally mounted link carried near another car end adapted to oscillate said latch and to interlock therewith.

7. In combination in a car coupling, a draft member and a rigid brace therefor both extending beyond a car end, a pivot

support carried at the extended ends of said draft member and brace, a link pivotally connected with said support, an oscillatory gravity latch carried near another car end, and a stop therefor, said link being adapted to oscillate said latch and to interlock therewith and said brace being adapted to drive said latch against said stop when the car ends approach each other. 20

In witness whereof I have hereunto set 25 my hand in the presence of two witnesses.

VICTOR WILLOUGHBY.
